CATHODE RAY TUBE

Dennis Gabor, Rugby, England, assignor to General Electric Company, a corporation of New York

Application August 4, 1938, Serial No. 223,089
In Great Britain January 3, 1938

9 Claims. (Cl. 250—27)

The present invention relates to cathode ray tubes employed in the art for oscillographic and television purposes.

For deflecting an electron beam across a cathode ray tube it is customary to employ one or more pairs of oppositely positioned plates. These plates are usually of concave configuration with the concavity facing the beam so as to increase the homogeneity of the electric fields between the plates. The electrodes may have a uniform curvature so that when mounted in the tube, they form the outline of a circle. Sometimes, they take an angular shape so as to define the outline of a square or rectangle. However, while noticeable improvement by way of increased homogeneity of field is obtainable by electrodes of the character specified, there is still a sufficient lack of uniformity of field over the entire path taken by the beam to give rise to distortion of the deflecting forces which act on the beam.

An object of the present invention is to provide an improved deflecting structure by which the electrostatic deflecting field presented to an electron beam over its entire length of travel is of a homogeneous character in order that the amount of deflection throughout the path of the beam will vary accurately in accordance with the electric potential applied to the deflecting electrodes. This object is attained in brief by providing within the deflecting structure additional electrodes, the field of which combines with and modifies the field of the structure to the extent necessary to give complete homogeneity to the deflecting field over a large area.

The invention will be better understood when reference is made to the following specification and the accompanying drawings in which Fig. 1 is a cross-sectional view of an oscillograph tube employed in accordance with the present invention; Fig. 2 is a circuit diagram showing electrical connections to the tube in accordance with one form of the invention; Fig. 3 is a graph of the equipotential lines obtained when the tube is connected in accordance with the circuit of Fig. 2, and Fig. 4 is a graph of equipotential lines obtainable when the electrodes are connected in a modified manner.

Referring specifically to Fig. 1, numeral 1 designates the glass envelope of a typical form of cathode ray tube which has a portion of uniform diameter and a long, flared portion closed by an arcuate portion 2. On the interior of this arcuate portion there is provided a layer 3 of material such as willemite, which fluoresces

when struck by electrons. The other end of the envelope terminates in a reentrant stem 4. Within the envelope and mounted from the stem 4 there is an indirectly heated cathode 5 which is heated by a filamentary member 6 and serves as a source of electrons. This stem also carries an apertured disk 7 positioned directly in front of the cathode 5 and the function of which is to focus or otherwise control the electrons. There is a metal disk 8 positioned on the opposite side of the grid 7 from the cathode 5, this disk having an opening through which the electrons emerge. The purpose of the disk 8 is to provide additional control of the focus, also to give high acceleration to the electrons emitted from the cathode so that the elements 5, 7 and 8 constitute a so-called "electron gun." Obviously, any other suitable form of electron gun may be employed.

The interior of the flared portion of the envelope is coated with a layer of metal 9 such as copper, the outer edge of the coating terminating short of the fluorescent layer 3. A conductor 10 is taken from this coating to the electrode 8. The purpose of the coating 9 is to maintain the velocity of the electrons through the flared portion of the envelope.

For deflecting the beam as it emerges from the opening in the electrode 8, there is provided a deflecting structure which consists preferably of two pairs of electrodes 11, 12, 13, and 14 positioned diagonally opposite one another. These electrodes, when assembled, are spaced from one another and are flared outwardly in the longitudinal direction to give the appearance of a horn. These electrodes are of marked concave shape in cross-section, and this shape may extend from an ordinary curvilinear configuration to an L-shape having corners. If the electrodes are of an arcuate shape, they form, when assembled, the outline of a circle, and when they are of an L-shape, they form the outline of a square or rectangle. The last-mentioned shape is illustrated in Fig. 2.

The deflecting electrodes may be mounted within the envelope in any suitable manner, for example, by means of conductors 15 (Fig. 1) which insulatingly pass through the coating 9 and are sealed in the glass envelope. A deflecting electrode structure such as described up to this point is well known in the art, and its purpose is to provide a homogeneous field so as to reduce distortion between the amount of movement of the electron beam and the potentials applied to the deflecting electrodes. However, it

as been found that electrodes of this character do not give that high degree of homogeneity of field which is found to be necessary, and in accordance with the present invention, I provide an improvement in the structure by which a much higher degree of homogeneity of field can be obtained and the field is homogeneous over a much larger area. The improvement consists essentially in providing a plurality of charged conductors 16 (see Fig. 2), positioned within the interior of the deflecting structure and respectively adjacent the median line of each electrode. These conductors therefore are located near each corner of the rectangular deflecting structure. The conductors should be of concentrated form, as shown, and in this connection may be described as being "of generally filamentary character." It should be understood, however, that the foregoing quoted phrase, as used herein and in the appended claims, is not to be construed as limited to conductors of a circular cross-section but, on the contrary, to be interpreted as including all small-sectioned conductors regardless of their configuration.

Fig. 2 illustrates a typical circuit arrangement which might advantageously be employed in connection with the tube such as described. As will be seen in this figure, the heater 6 is energized by a battery 18, and the cathode 5 is connected to one side of the heater. The grid member 7 is connected to the cathode 5 through a battery 9 and an alternator 20 which is intended generically to indicate a source of control or signal current, which may be alternating current or interrupted or continuous direct current. The accelerating electrode 8 and the coating 9 connected thereto derive positive potential from a battery 21. It will be noted that the electrodes 11, 12, 13, and 14 of the deflecting structure and the contained conductor 16 are shown in a different plane from the remaining electrodes in order to illustrate more clearly the connections to these various electrodes. It will be understood, however, that the deflecting electrodes actually extend lengthwise of the tube and in the same direction as the electron gun, similarly to that shown in Fig. 1.

As the electrons emerge from the opening in the electrode 8, they are caused to be deflected between the oppositely positioned electrodes 12 and 14 of the deflecting structure by means of the variable potentials applied to a transformer 2. The remaining pair of oppositely positioned electrodes 11 and 13 does not have a deflecting potential applied thereto but instead these electrodes are electrically connected together by a conductor 23. The electrodes are also electrically connected by means of a conductor 24 to a mean potential tap 25 on the transformer secondary. The electrodes 11 and 13 are preferably maintained at a positive potential with respect to the cathode 5 by a battery 26, and serve to give the electrons within the deflecting structure an accelerated velocity. As stated hereinbefore, as the electrons leave the deflecting structure, they continue to move forward at a high velocity, due not only to the initial speed acquired in passing through the electrode 8 and between the electrodes 11, 13 but also due to the positive potential applied to the conical electrode or metal layer 9. As these electrons reach screen 3 which they strike with considerable force, a light trace is produced on the screen. The length of this trace at any particular time is of course dependent on the potential conditions within the tube

and particularly the magnitude of the voltage applied across electrodes 12, 14.

As stated hereinbefore, conductors 16 are provided for the purpose of increasing the homogeneity of the field within the deflecting structure. These conductors are preferably brought out from the deflecting structure by separate taps to a common conductor 27 which is connected through the conductor 24 to the mid-point or mean potential tap of the transformer 22. The connection between conductor 27 and each conductor 16 has been diagrammatically illustrated in Fig. 2 as a wire passing through all of the conductors, but it will be understood that the conductors 16 have their own individual connection leading to the common conductor 27 and preferably brought out from the deflecting electrode in such a manner as to interfere as little as possible with the electric fields produced by the electrodes 11, 12, 13, and 14.

It is apparent that in addition to the function described hereinbefore of accelerating the electrons through the deflecting structure, electrodes 11, 13 also serve to modify the deflecting field set up by the electrodes 12, 14, resulting in what may be termed a "composite field." It has been found that when the conductors 16 are additionally provided, this composite field is still further modified by the field of the conductors to the extent of providing a field of remarkable homogeneity in which the equipotential lines of force are uniformly distributed throughout an area almost as large as the area contained within the deflecting structure. The composite field as modified by the field of the conductors 16 is illustrated in Fig. 3 in which the reference characters designate elements similar to those carrying the same designations in Fig. 2. The transformer 22 serves to apply across the electrodes 12, 14 a deflecting potential which causes the electrons to move in the direction indicated by the arrow. Electrodes 11, 13 are connected by the conductor 23 to the mid-tap on the transformer secondary, and the conductors 16 are electrically connected together to the same mid-tap.

A consideration of the potentials applied between the electrodes 11, 12, 13, and 14 with respect to one another and with respect to the conductors 16 will show that there is a potential difference between the ends of the adjacently positioned electrodes 11, 12, 13, and 14, also a potential difference between the upper right-hand conductor 16 and the electrode 12, and between the lower left-hand conductor 16 and the electrode 14. However, there is no potential difference between the upper left-hand conductor 16 and the electrode 11 nor between the lower right-hand conductor 16 and the electrode 13. These potential differences are obtained from the voltages applied either across the entire secondary 22 or across one-half of the winding 22, as will be readily apparent from a study of this figure. The electrostatic lines of force due to the various potentials will form a pattern similar to that shown in Fig. 3. It will be noted that the area enclosed by the dotted square 28, in which the equipotential lines are almost equidistant and have small curvatures, is almost as large as the entire space contained within the deflecting structure. Consequently, a cathode-ray tube provided with the improved structure including the conductors 16 provides a large area over which the beam can move through a field of marked homogeneity.

The selected system of representation is such

that each of the equipotential lines represents a fixed potential difference from the next adjacent line. Consequently a series of equally spaced lines represents a condition in which the deflecting-voltage gradient is constant throughout the region of equal spacing. Furthermore, in any region in which the equipotential lines are straight or have small curvature, the direction of the beam deflection will be the same irrespective of the portion of the region in which such deflection is initiated. It has been found that if the conductors 16 be omitted, the area over which the field is homogeneous is considerably reduced, and in some cases, entirely eliminated. The advantage of the increased homogeneity of field brought about by my improved deflecting structure is that the beam will be deflected proportionately to the variations in control potential over a considerable distance in the deflecting direction. Consequently, when it is desired to deflect the beam in two directions at right angles to one another as in the case of scanning a picture or image, the area over which the beam can be deflected throughout a homogeneous field is similarly increased and this tends to reduce distortion in the reproduction of the picture or image. This distortionless two-directional field can be obtained if desired, in accordance with my invention, by providing two complete sets of the deflecting structures shown in Fig. 3 and arranged adjacent one another, both structures being provided with the additional conductors 16 and the proper potentials to eliminate distortion in each of the two directions in which it is desired to deflect the beam.

The actual size of the deflecting electrodes and the spatial distances therebetween, also the distances between the conductors 16 and the electrodes, and the size of the conductors, as well as the other spatial and dimensional sizes and applied potentials, can best be determined by experiment and will obviously depend on the extreme areas or distances over which it is desired to deflect the beam. I have found that particularly good results are obtainable when the wires 16 have a diameter of about 1.5% of the side of the square formed by the deflector electrodes and are positioned a distance apart equal to about 78% of the distance between the corners of the square.

It is obvious that any means may be employed to give the proper potential difference between the various electrodes, for example, continuous or interrupted direct-current voltages obtained from batteries or from any other source of control voltage connected in such a manner that the equipotential lines of force contained within the deflector structure will have substantially the configurations shown in Fig. 3. Instead of using two sets of deflecting structures for deflecting the electrons in two directions, it is obvious that only one of the improved deflecting structures may be used for deflecting the electrons in one direction, and a magnetic form of deflecting structure used for deflecting the electrons in another direction. Various other modifications will occur to those skilled in the art.

Another form which my invention might take and one in which the deflection is in the horizontal rather than in the diagonal direction is shown in Fig. 4. As in the case of Fig. 3, the conductors 16 are all connected together to the mid-tap of the transformer 22 which provides the deflecting voltage. But the electrodes 11 and 14 are now connected together, and similarly, elec-

trodes 12 and 13, so that the deflecting potential is applied between two groups of electrodes, of which one group is constituted of electrodes 11 and 14 and the other group is constituted of electrodes 12 and 13. A study of the circuit diagram will show that there is a potential difference between electrodes 11 and 12, also between electrodes 13 and 14, but no potential difference between electrodes 11 and 14 nor between electrodes 12 and 13. But there is a potential difference between all of the conductors and all of the electrodes. The fields introduced by these potential differences are roughly those illustrated in the figure, and it will be noted that a large square with its apexes vertical or horizontal can be drawn over an area in which the equipotential lines occur in a homogeneous array. Due to the manner in which the deflecting electrodes are connected, the direction of deflection is horizontal as indicated by the arrow. It will be noted that the length of the diagonal of the square 29 which encloses the area over which the equipotential lines are uniformly distributed is approximately 80% of the distance between any two opposite deflector plates, that is, 80% of the maximum deflection that is geometrically possible. This fact has been verified experimentally.

While I have described my invention more particularly in connection with deflector plates of a square or L-shaped cross-section, it will be understood that the increase in homogeneity of the static field introduced within the deflecting structure by the conductors 16 may also be advantageously employed in connection with deflector electrodes of other shapes than those illustrated and described. The spacing between the electrodes and between the conductors and the electrodes, also the potentials applied respectively to each of these elements will be different for the different types and shapes of deflector electrodes.

What I claim as new and desire to secure by Letters Patent of the United States, is:

1. In combination, a cathode ray tube comprising a source of electrons, means for accelerating said electrons, and a structure for deflecting the electrons, said structure including a plurality of separate concave electrodes arranged to form an enclosure, means for applying a cyclically varying potential between at least certain ones of said electrodes to establish a deflecting field within the enclosure, and means within the enclosure for modifying the deflecting field to produce uniform deflecting gradients over substantially the entire region of deflection of the electron beam, said last named means comprising a plurality of discrete conductors of generally filamentary character charged to such potential as to produce local distortion of the deflecting field in the vicinity of each conductor.

2. In combination, a cathode ray tube comprising a source of electrons, means for accelerating said electrons, and a structure for deflecting the electrons, said structure comprising a plurality of L-shaped electrodes arranged to form a generally rectangular enclosure, means for applying a potential between at least certain ones of said electrodes to establish a deflecting field within the enclosure and within the enclosure for modifying the deflecting field to produce uniform deflecting gradients over substantially the entire region of deflection of the electron beam, said last mentioned means comprising a plurality of discrete conductors which are respectively positioned adjacent to the various L-shaped electrodes and which are charged to such a potential as to pro-

duce local distortion of the deflecting field in the vicinity of each conductor.

3. A cathode ray tube comprising a source of electrons, means for accelerating said electrons, and a structure for deflecting the electrons, said structure including a plurality of separate concave electrodes arranged to form an enclosure, and a plurality of discrete conductors of generally filamentary dimensions respectively positioned within the concavities of the various electrodes, said conductors being adapted during the operation of the tube to modify the electrostatic field within the said enclosure.

4. In combination, a cathode ray tube including an electron gun and an electron deflecting structure, said structure comprising a plurality of pairs of oppositely positioned electrodes to form a common enclosure, means for applying a cyclically varying potential between the oppositely positioned members of one of said pairs to provide a deflecting field for the electron beam within the enclosure, means for maintaining another of said pairs of electrodes at a relatively fixed potential to produce a first desired modification of the deflecting field and means for further modifying the deflecting field to produce uniform deflecting gradients over substantially the entire region of deflection of the electron beam, said last named means comprising the combination of a plurality of discrete conductors of general filamentary character positioned within the said enclosure and means for maintaining said conductors at a relatively fixed potential.

5. In combination, a cathode ray tube comprising an electron gun and an electron deflecting structure, said structure comprising a plurality of pairs of oppositely positioned concave electrodes arranged to form a common enclosure, an alternating current source for applying a cyclically varying potential between the oppositely positioned members of one of said pairs to provide a deflecting field for the electron beam within the enclosure, means for maintaining another of said pairs of electrodes at a relatively fixed potential to produce a first desired modification of the deflecting field and means for further modifying the deflecting field to produce uniform deflecting gradients over substantially the entire region of deflection of the electron beam, said last named means comprising the combination of a plurality of discrete conductors of general filamentary character respectively positioned within the concavities of the various electrodes and means for maintaining said conductors at the mean potential of said alternating current source.

6. In combination, a cathode ray tube comprising an electron gun and an electron deflecting structure, said structure including a plurality of pairs of oppositely positioned L-shaped elec-

trodes arranged to form a generally rectangular enclosure, a source of alternating current for applying a cyclically varying potential between the oppositely positioned members of one of said pairs to provide a deflecting field for the electron beam within said enclosure, means for maintaining the other of said pairs of electrodes at the mean potential of said alternating current source, a plurality of discrete conductors of generally filamentary character respectively positioned in each corner of the rectangular enclosure and means for maintaining said conductors at the same potential as the said other of said pairs of electrodes.

7. In combination, a cathode ray tube comprising a source of electrons, means for accelerating said electrons and an electrode deflecting structure, said structure including four concave electrodes arranged to form a substantially closed configuration, alternating current means for applying a deflecting voltage between one pair of adjacent electrodes and the other pair of electrodes and means for modifying the deflecting field within the electrodes to increase its uniformity, said last mentioned means comprising a plurality of discrete conductors of generally filamentary character positioned within the said hollow configuration and respectively adjacent each of said electrodes, and means for charging said conductors to a relatively fixed potential.

8. In combination, a cathode ray tube comprising a source of electrons, means for accelerating said electrons and a structure for deflecting the electrons, said structure including four L-shaped electrodes arranged to form a substantially rectangular enclosure, a plurality of discrete conductors of generally filamentary character positioned respectively in each corner of the said rectangular enclosure, means for applying a cyclically varying deflecting voltage between one pair of adjacently positioned electrodes and the other pair of electrodes, and means for maintaining said conductors at a common potential different from the potential of each of said L-shaped conductors.

9. In combination, a cathode ray tube comprising a source of electrons, means for accelerating said electrons, and a structure for deflecting the electrons, such structure including four L-shaped electrodes arranged to form a substantially rectangular enclosure, a plurality of discrete conductors of generally filamentary character positioned respectively in each corner of the rectangle, an alternating current source for applying deflecting voltage between one pair of adjacently positioned electrodes and the other pair of electrodes, and means for maintaining all the said conductors at the mean potential of the said alternating current source.

DENNIS GABOR. 60

CERTIFICATE OF CORRECTION.

Patent No. 2,212,396.

August 20, 1940.

DENNIS GABOR.

It is hereby certified that error appears in the printed specification of the above numbered patent requiring correction as follows: Page 3, second column, line 24, for "betwen" read --between--; line 68, claim 2, before the word "within" insert --means--; page 4, first column, line 17, claim 4, after "electrodes" insert --arranged--; and that the said Letters Patent should be read with this correction therein that the same may conform to the record of the case in the Patent Office.

Signed and sealed this 8th day of October, A. D. 1940.

Henry Van Arsdale,

(Seal) Acting Commissioner of Patents.
